UNITED STATES PATENT OFFICE.

SAMUEL C. WISER, OF CHICAGO, ILLINOIS.

STOCK-CAR.

SPECIFICATION forming part of Letters Patent No. 274,240, dated March 20, 1883.

Application filed July 20, 1882. (No model.)

To all whom it may concern:

Be it known that I, SAMUEL C. WISER, a citizen of the United States of America, residing at Chicago, in the county of Cook and State 5 of Illinois, have invented certain new and useful Improvements in Stock-Cars, of which the following is a specification.

My invention relates to that class of stock-cars which are arranged for feeding and watering the stock during transportation; and it 10 particularly relates, in part, to improvements on the stock-car for which which I have previously made application for patent, which application was allowed May 4, 1882, Serial No. 15 57,824.

My invention consists in certain combinations and arrangements of parts, as hereinafter more fully set forth, with reference to the accompanying drawings, in which—

20 Figure 1 is a side elevation of a stock-car supplied with my improvements. Fig. 2 is a transverse sectional view of the same, and Figs. 3 to 8, inclusive, detail views of some of the various parts more particularly hereinafter referred to.

Similar parts are represented by similar letters throughout the several views.

In the drawings, A A represent a stock-car provided on each side with a series of buckets, B, arranged to be turned in or out by means of racks c and pinions p, and having water-pipes P leading thereto, in the manner and for the purpose more fully set forth in the application hereinabove referred to.

35 C is a partition or stall, hung by ropes rr from a shaft, s, journaled in suitable bearings near the top of the car, and provided at either or both ends with cranks f, by means of which the ropes r may be wound up, drawing the partitions up to the top of the car, where they are hooked up, as shown in Fig. 7, by hooks h. These partitions are for the purpose of separating the stock when the car is filled, and for this purpose there will be used a number of 45 partitions equal to the number of buckets, less one, which are to be let down between the stock when in place, but drawn up out of the way, as before described, when unloading or when the car is to be used for other purposes.

50 Upon the top of the car, along each side, is a box or trough, D, from which lead a number

of pipes or spouts, d, to the buckets B. The troughs are to contain the feed, and they are each provided with a slide, b, having a number of openings, b', (see Fig. 8 for detail,) equal to the number of spouts d, and are connected at one end to a hand-lever, E. If it is desired to feed the stock, the slide b, by means of the hand-lever E, is drawn along until the openings b' coincide with the mouths of the spouts d and the feed runs down through said spouts into the buckets B.

The buckets B, instead of being secured rigidly to the rods a, as heretofore, I make detachable by forming a socket, e, on the bucket B, which fits on the square end e' of the rod a. (See Fig. 6.) By this arrangement, upon raising the bucket slightly it may be detached from the rod a or replaced thereon at will.

The frame F, which fits in the doorway, is 70 so arranged that one bucket or two may be used therein, as the case may require.

On the end of each of the water-pipes P is a valve, n, provided with a float, o, (see Fig. 6,) which, when the bucket B is filled to a certain depth, closes the valve and shuts off the water, thus preventing the buckets from overflowing on the car-floor.

Having thus described my invention, what I claim as new and original, and desire to secure by Letters Patent, is—

1. In a stock-car, the bucket B, provided with a socket, e, in combination with a rod, a, having square end e', substantially as described and shown.

2. In a stock-car, the combination of the rotatable buckets B, troughs D, having spouts d, leading to said buckets, and slides b, having notches b', and hand-lever E, substantially as and for the purpose described.

3. In a stock-car, the combination of the vertically-movable partitions C, shafts s, having cranks ff, ropes rr, connecting said shafts and partitions, and hooks h h, all substantially as shown and described.

In testimony whereof I affix my signature in presence of two witnesses.

SAMUEL C. WISER.

Witnesses:

CLACK S. HARRISON,
FRANK JOHNSON.
